UNITED STATES PATENT OFFICE.

ANTHONY SNIEGOCKI, OF OAKLAND, CALIFORNIA.

COMBINATION SHAVING BRUSH AND SOAP HOLDER.

Application filed October 11, 1922. Serial No. 593,856.

To all whom it may concern:

Be it known that I, ANTHONY SNIEGOCKI, a citizen of Poland, residing at Oakland, county of Alameda, and State of California, have invented new and useful Improvements 5 in Combination Shaving Brush and Soap Holders, of which the following is a specification.

This invention relates to a combination 10 shaving brush and soap holder.

The object of the present invention is to generally improve and simplify devices of the character described; to provide a combination shaving brush and soap holder so 15 constructed that the soap in the form of a stick may be projected downwardly through the bristles, thereby permitting application of soap and lathering of the face in one operation; to provide means for advancing 20 the soap stock as it is used or wears away, said means also serving as an enclosure and protector for all of the soap, except the small portion required for actual use; and further to provide a reversible cap which 25 will serve three functions, first that of a handle, secondly that of a closure or cap for the exposed end of the soap stick, and third that of a stand which will support the brush in an inverted position, thus permitting the 30 water remaining on or between the bristles to drain away without collecting around the head of the bristles. Other objects will hereinafter appear.

One form which my invention may assume is exemplified in the following description and illustrated in the accompanying drawings, in which—

Fig. 1 is a central, vertical, longitudinal section of the combined shaving brush and 40 soap holder.

Fig. 2 is a cross section on line 2—2, Fig. 1.

Fig. 3 is a side elevation of the brush partly broken away and partly in section, 45 showing the cap employed as a stand upon which the brush may be supported in an inverted position.

Referring to the drawings in detail, and particularly to Figures 1 and 3, A indicates 50 the head of the brush, B the handle portion, and C the bristles or the brush proper. The bristles are in this instance secured in the head member A in any suitable manner, for instance by being cemented, rubber set, or 55 otherwise secured as indicated at 2. The head proper consists of an inner centrally

disposed sleeve 3, and an exterior bell shaped member 4. An annular chamber or recess is formed between the sleeve 3 and the member 4, and this chamber is employed for the 60 reception of the butt ends of the bristles, and also for the cement or other material whereby they are secured. The bristles secured in the manner described leave a central passage, through which a tube 5 extends. This tube is slidably mounted in the inner sleeve 3 and is normally held against sliding movement merely by a tight or frictional fit. The tube serves two functions, first that of a handle and secondly that of 65 a holder for a cylindrical stick of shaving soap, as indicated at 6. The stick of soap is inserted through the upper end of the tube 5 and is forced downwardly through the tube until a small portion thereof projects through the lower end of the tube between the bristles as indicated at 7. A plunger 8, constructed of cork, or any suitable material, is placed on top of the soap stick and this is employed for the purpose 70 of advancing the stick of soap as it is used or wears away.

The device as a whole is also provided with a cap or closure 9, which assumes the 75 position shown in Fig. 1, when the brush is being employed while shaving. This cap serves three functions, first that of a handle as it cooperates with the tube or member B, secondly that of a holder for the shaving stick or soap indicated at 6, and third that 80 of a base by which the brush may be supported in an inverted position as shown in Fig. 3. When so employed it is merely necessary to remove the cap from the upper end of the tube 5, then to force the tube 5 85 downwardly through the bristles until it projects below the ends of the same, and finally to apply the cap to the lower end as shown in Fig. 3, and when so applied it 90 serves as a base and will support the brush in the position shown. It also serves as a protector or closure for the exposed end of the soap when the bristles are being washed or cleaned, for instance, after shaving.

Positioning of the brush as shown in Fig. 3 is ideal as it permits the water adhering or collecting between the bristles to drain 100 downwardly away from the head member A, thus preventing rotting of the bristles and softening of the cement or other material 105 by which the bristles are secured in the head.

The cap 9 is frictionally secured when

applied to either end of the tube 5, and as such its position may be quickly reversed.

The projection or positioning of the tube 5 may also be quickly adjusted to project or 5 retract the soap with relation to the bristles as this tube is also frictionally secured. The device is therefore readily operated and adjusted, and it furthermore forms a compact unit which may be readily stored away when 10 travelling or otherwise, and as such should be particularly useful for soldiers, sailors and travelling men in general. It will obviously be just as useful in the home and as such should find a wide field of general 15 utility.

While certain features of the present invention are more or less specifically illustrated, I wish it understood that various changes in form and proportion may be 20 sorted to within the scope of the appended claims, similarly that the materials and finish of the several parts employed may be such as the experience and judgment of the manufacturer may dictate or various uses 25 may demand.

By referring to Fig. 1, it will be noted that the plunger 8 is connected with the soap stick through means of a flexible wire, such as indicated at 30. The lower end of this 30 wire is hook-shaped to engage the stick and as such forms a connection between the stick and the plunger. This is of importance as the soap stick might not always form a frictional fit with relation to the tube. Such a 35 defect would be taken care of by connecting the soap stick and the plunger as this is made of cork and will therefore always maintain the frictional resistance desired, and it will furthermore serve as a holder for 40 the soap when it is worn away to a short stub.

Having thus described my invention, what I claim and desire to secure by Letters Patent is—

45 1. A device of the character described comprising a head member, bristles secured to the head member and arranged in circular formation to produce a central opening, a tube slidably mounted in the head member, and adapted to be extended downwardly 50 through the bristles, a soap stick carried by the tubular member and projecting through the lower end thereof, said tube frictionally

fitting the head member, and permitting vertical adjustment of the tube and the soap carried thereby with relation to the head member and the bristles, and means frictionally fitting the interior of said tube and adapted to be manually actuated to advance the soap stick with relation to the tube. 55 60

2. A device of the character described comprising a head member, bristles secured to the head member and arranged in circular formation to produce a central opening, a tube slidably mounted in the head member and adapted to be extended downwardly through the bristles, a soap stick carried by the tubular member and projecting through the lower end thereof, said tube frictionally fitting the head member and permitting vertical adjustment of the tube and the soap carried thereby with relation to the head member and the bristles, a cork frictionally engaging the interior of the tube, and means forming a connection between the soap stock 70 and said cork, said cork adapted to be manually depressed to advance the soap stick with relation to the tube. 75

3. A combined shaving brush and soap holder comprising a central sleeve, a bell shaped annular member secured to the sleeve and forming an annular chamber exteriorly thereof, bristles secured in said annular chamber and arranged in circular formation and forming a central passage between the 80 bristles, a tube frictionally supported by the inner sleeve and vertically adjustable therein, a cylindrical stick of soap adapted to be received by the tube and projecting a slight distance beyond one end thereof, and a reversible tubular shaped cap adapted to frictionally engage either end of the tube. 85 90

4. A device of the character described, comprising a head member, bristles secured to the head member and arranged in circular 95 formation to produce a central opening, a tube frictionally engaging the head member and slidably mounted therein, a cap adapted to be received by either end of the tube, said cap being adapted to serve as a handle when 100 received on the upper end of the tube, and said cap serving as a supporting base for the brush when received on the lower end of the tube.

ANTHONY SNIEGOCKI.
